UNITED STATES PATENT OFFICE.

ELIAS U. BENEDICT, OF AURORA, ILLINOIS.

STOCK-CAR.

SPECIFICATION forming part of Letters Patent No. 399,821, dated March 19, 1889.

Application filed November 23, 1888. Serial No. 291,667. (No model.)

To all whom it may concern:

Be it known that I, ELIAS U. BENEDICT, a citizen of the United States, residing at Aurora, in the county of Kane and State of Illinois, have invented a new and useful Improvement in Stock-Cars, of which the following is a specification.

The object of my improvement is to provide a car for the shipment of live stock, and especially horses, the construction of which shall involve folding partitions adapted to be readily adjusted in positions to afford stalls for the animals, and as readily folded back against the side or sides of the car to clear the latter and adapt it to be used for the shipment of lumber, grain, or other kinds of merchandise. By my improved construction the use of the car for transporting live stock from the place of shipment to the destination does not necessitate its use for the same purpose on the return journey, nor that it shall be returned empty, but permits ready adjustment of its interior into an ordinary freight-car.

My invention consists in the general construction of my improved stock-car; and it further consists in details of construction and combinations of parts.

In the drawings, Figure 1 shows a transverse section of a car arranged by means of my improved construction as a stock-car. Fig. 2 is a horizontal section of a broken portion of the same, illustrating the partitions in their extended and folded positions, the section being taken on the line 2 2 of Fig. 1 and viewed in the direction of the arrows. Fig. 3 is an enlarged view showing one of the folding partitions with which the stalls are formed and parts connected therewith and with which it is connected in broken elevation. Fig. 4 is a sectional view of a detail on the line 4; and Figs. 5 and 6 are sectional views taken, respectively, on the line 5 and 6 of Fig. 3, and viewed as indicated by the arrows.

A is a car, which may involve the construction of an ordinary box-car. The timbers *r*, which extend transversely across the interior of the car near the roof, are preferably equidistant and such distance apart as will correspond with the desired width of stall, which is formed, in the manner hereinafter described, between each adjacent pair thereof.

I form the stalls with partitions *B*, which, when not required to be used for their purpose of defining the stalls, may be folded against the wall of the car. Each partition is formed, preferably, of wood, and has provided at its lateral edges, near opposite ends, straps *q*, affording sockets *p* in line with the edges of the partition to receive at one of the said edges the opposite ends of a metal rod, *o*, which may be partly countersunk into such edge, as shown, and at the other of the said edges a similar sliding rod, *n*, formed at its upper end into a latch, *n'*, and likewise partly countersunk, if desired, into the adjacent edge of the partition, and rendered accessible to the hand near its middle, where it is provided with a stop, *n''*, by forming a recess, *n''*, in the edge of the partition, and the rods *o* and *n*, which need not be greater than seven-eighths of an inch in diameter in the main, may be enlarged to an inch in diameter toward their opposite ends, as illustrated, where they enter the sockets *p* of the straps *q*. Each partition should involve a width somewhat less than that of the space between each pair of timbers *r*, (which is about two feet and four or five inches, or the ordinary or desired width of a stall,) so that it will fit flatwise between them against a wall of the car, to enable it to be folded in the manner and for the purpose hereinafter described, and the length of each stall should, by preference at least, be about a foot longer than the width of the partition, so as to separate at least the hind quarters of the different animals in adjacent stalls and not leave sufficient space between the edges of the partitions nearest the wall and the latter to enable the hind legs of the animals to enter adjacent stalls or permit the animals to kick each other.

On one side of each timber *r*, and extending from near the wall of the car, is secured a casting, *C*, in the form of an angle-iron opening downward and affording a guideway for the upper end of the rod *o*, which extends into it beyond the end of the partition, and directly below and parallel with the guideway *C* is a casting, *D*, in the form of a slotted laterally-flanged guide to receive the lower projecting end of the rod *o*, and having sockets *m* and *m'*, open at their bases near its opposite ends, the casting, which corresponds substantially in length (about a foot) with the

- casting C, being countersunk into the floor of the car, and the sockets extending through openings in the floor provided to receive them. Adjacent to the socket m of each casting D, 5 except that nearest one end of the car and close to the wall, is a thimble, l , open at its base and extending through the car-floor; and at a distance transversely to the car from the socket m' in each casting D, corresponding 10 with the distance longitudinally of the car at which a thimble, l , is located from a socket, m , is countersunk through the car-floor a thimble, k . Directly above each thimble k , on the timber r , in line with it, is secured a catch, i .
- 15 The normal position of the partitions B when the car A is not arranged for use as a stock-car is flat against the car-wall, when the upper and lower ends of each rod o extend, respectively, into a guideway, C, and a socket, 20 m , below such guideway, and the lower end of each rod n extends into a thimble, l . With the interior of the car thus arranged, the latter is adapted to serve the purpose of any ordinary box-car.
- 25 To arrange the car for shipping stock, the rod n of each partition is raised by grasping it at the recess n' to release its lower end from a thimble, l , when the partition is swung around on the ends of the rod o to cause it 30 to extend transversely to the car, whereupon it is raised bodily to lift the lower end of its rod o out of a socket, m , and then drawn forward till the lower end of the rod o enters the socket m' of the casting D, and the rod n coincides with the thimble k in line with such casting. Thereupon the lower end of the rod n is caused to enter the thimble k and the latch n' at its upper end to engage with the catch i , whereby each partition, so extended, 35 is securely locked and forms with an adjacent partition or with the end of the car to which it is adjacent a stall, E.
- To reconvert the stock-car into a box-car devoid of internal obstructions, each partition is raised to free its rods o and n from thimbles m' and k , and to disengage its latch n' , when it is turned slightly to one side to cause the latter to clear the catch i , and moved back in the guide-castings D and C till the 40 rod o enters the socket m , the partition being then turned on the pivot afforded by the last-named rod toward a thimble, l , adjacent to an opposite partition, into which thimble the rod n , which may have been previously raised 45 to clear it, is introduced.
- The temporary stalls may each be formed in the manner described after the animal to occupy it has been placed in position, or the animals may be introduced into the stalls 50 after the latter have been so formed, when they may be hitched or tied to or near the side of the car opposite that from which the partitions extend and where a temporary or removable feed-trough (not shown) may be provided.
- 55 While the partitions provided on only one side of the car in the manner described are

shown in the actual use of my improvement to suffice, it is within the spirit of my invention to provide partitions similarly constructed and operated, also, at the opposite side of the car, though, being then necessarily in two sets on opposite sides of the car-door, the two sets should be arranged to fold in opposite directions with relation to the 75 door-opening. If the partitions be provided, as thus suggested, on each side of the car, the animals need not necessarily be hitched or tied in the stalls thereby formed.

Ventilation may be secured by means of ordinary rotary ventilators, F, near the base of a side, and by sliding doors G, for controlling openings provided toward the upper ends of opposite sides of the car.

What I claim as new, and desire to secure by Letters Patent, is—

1. In combination with a car, A, a partition, B, pivotally supported to stand vertically in the car and disconnected from the side of the car against which it is to be folded, and guides 90 extending transversely of the car from near one side thereof for the upper and lower edges of the partition, whereby the partition may be turned on its pivotal support to extend parallel with and be thus folded against an inner side of the car, and be turned from its folded position to extend in the direction of the said guides, and be slid toward the opposite inner side of the car, and thus form a stall, E, open between the rear edge of the 100 partition and the adjacent car-wall, substantially as described.

2. In combination with a car, A, an overhead guideway, C, a guideway, D, having end sockets, m and m' , and secured to the car-floor in line with the guideway C, a thimble, l , and a thimble, k , in the car-floor, respectively adjacent to the wall and in line with the guideway D transversely of the car, and a partition, B, having rods o and n at opposite 110 edges, substantially as described.

3. A convertible stock-car comprising, in combination with a car, A, overhead transverse timbers r , guideways C, supported on the timbers, guideways D, having end sockets, m and m' , and countersunk into the car-floor, one directly below each guideway C, to extend transversely from near a wall of the car, partitions B, having rods o and n at their opposite lateral edges, each rod o extending at its 115 opposite ends into coincident guideways C and D, thimbles l , countersunk into the car-floor adjacent to the said wall of the car and located each to receive the lower end of a rod, n , when the partition is folded against the 125 side of the car, and thimbles k , countersunk into the car-floor, one in line with each guideway D, and each located to receive the lower end of a rod, n , when the partition is drawn out, to cause its rod o to enter a socket, m' , 130 substantially as described.

4. A convertible stock-car comprising, in combination with a car, A, overhead transverse timbers r , equidistant apart, guide-

ways C, secured to the timbers, guideways D, having end sockets, m and m' , and countersunk into the car-floor, one directly below each guideway C, to extend transversely from 5 near a wall of the car, partitions B, having rods o and n at their opposite lateral edges, each rod o extending at its opposite ends into coincident guideways C and D, thimbles l , countersunk into the car-floor adjacent to 10 the said wall of the car and located each to receive the lower end of a rod, n , when the partition is folded against the side of the car, thimbles k , countersunk into the car-

floor, one in line with each guideway D, and each located to receive the lower end of a rod, 15 n , when the partition is drawn out, to cause its rod o to enter a socket, m' , latches n' on the upper ends of the rods n , and catches i , supported on the timbers r in positions to be engaged by the said latches, substantially as 20 described.

ELIAS U. BENEDICT.
